UNITED STATES PATENT OFFICE.

THOMAS ELLIOTT, OF CINCINNATI, OHIO, ASSIGNOR TO THE CINCINNATI CAR COMPANY, OF CINCINNATI, OHIO, A CORPORATION OF OHIO.

RAILWAY CAR.

Application filed December 14, 1923. Serial No. 680,604.

To all whom it may concern:

Be it known that I, THOMAS ELLIOTT, a citizen of the United States, residing at Cincinnati, in the county of Hamilton and State of Ohio, have invented certain new and useful Improvements in Railway Cars, of which the following is a specification, reference being had therein to the accompanying drawing.

10 This invention relates to improvements in railway cars, particularly to the double pivotal connection or articulation of the cars to the bolster of a truck common to two adjacent cars.

15 The principal object which the arrangement of the two independent pivotal supports enables me to carry into effect, is that of giving both cars perfect freedom to change their relative positions, one car 20 with the other, both horizontally and transversely—horizontally, as when going over a hill, one car being then on one side of the crest and the other on the other side, which tends to make an obtuse angle between the

25 two cars; and likewise when the cars reach the dip of a hill where the grade begins to rise, in which case the two bodies will assume another obtuse angle. And again, when there is a curve in the tracks, either 30 at the crest or at the dip, the cars can change not only their horizontal relation, but their lateral relation at the same time, due to the two independent pivots; so that all these movements are accommodated by reason of 35 the double pivoting of the cars to the bolster.

Another object of my invention is the provision of a double socketed base plate adapted to be carried by the bolster of a truck common to two cars and trunnions 40 carried by the cars, one trunnion for each socket.

A further object is to provide means for preventing either trunnion from jolting or otherwise getting out of its socket while the 45 cars are in use.

Another object in providing two independent sockets and trunnions, a set for each car, is to permit the removal of either car from the truck without interfering with 50 the continuance of the other car on the truck.

Another object in dividing the weight of the two cars between the two sets of sockets and trunnions is to prevent overloading either set of sockets and trunnions, which

otherwise would exclude the entrance of a lubricant between the socket and trunnion; but by dividing the total weight of both cars to be supported, the weight of neither is sufficient to exclude the entrance of the lubricant at the parts to be lubricated.

60 In the accompanying drawings, Fig. 1 is a partial plan view and sectional view of two adjacent cars each pivotally mounted on a common bolster.

Fig. 2 is a vertical longitudinal section 65 showing the bolster and the pivot sockets and trunnions.

Fig. 3 is an enlarged detail sectional view of the socket plates, the trunnions and the locking bolt by which the trunnions are 70 maintained in the sockets.

The numeral 1 indicates the car platforms of two adjacent cars which are to be pivotally mounted or articulated on a common bolster, and 2 a single truck whose wheels 75 are indicated at 3. The details of the truck I do not illustrate because they are not involved.

I also show a vestibule 4, which is adapted to be carried by the platforms and to 80 span the space between them and to afford through its openings 5 a passageway for passengers to travel from one platform to the other.

Between the bolster and the vestibule I 85 locate and provide resilient side bearings 6, which may be of any desired construction but are preferably built according to the disclosure of the side bearings in the application of Charles J. Ellis, filed the 14th 90 day of December, 1923, Serial No. 680,603.

Referring now to the double articulation, see particularly Figs. 2 and 3 where a base plate 7, preferably in the form of a heavy casting, is shown secured to the bolster 2. This plate is provided with semi-spherical sockets 8, adapted to receive similarly shaped pivot trunnions. These are indicated at 9, and are formed as a part of a general trunnion plate the body of which is 100 indicated at 10. To each car platform is secured in any convenient way, one of these trunnion plates, the outline of which is shown in dotted lines in Fig. 1.

Thus it will be seen that each of the two 10 adjacent cars is supported by its own pivotal connection with the same common bolster of a truck allotted to the function of

2
sustaining and carrying the adjacent ends of two cars.

In order to prevent the accidental displacement of the pivot trunnions from their sockets, I provide a locking device. The preferred form of this device consists of lugs 11 formed on the base plate 7 and adapted to receive and maintain a bolt 12, which fits within recesses or over shoulders 13 shown at 13. There is sufficient space left between the bolt and the shoulders to admit of the required movement of the trunnions in acting as pivots, yet the relation of the bolt to the trunnions is such that the latter 15 cannot be thrown out of their sockets by reason of the up and down vibrations of the cars, or in case of accident. This bolt 12 is removable so that either or both trunnions 20 may be removed from the sockets as desired, as in making repairs on the cars.

It will be observed also that by reason of the trunnion pivots being independent, either 25 may be removed for purposes of repairing or otherwise working on one of the cars without the expense and necessity of applying lifting jacks and other mechanisms to lift the other car as to which no repairs are needed.

Another feature of advantage and utility 30 in the use of the double trunnions is that each has to carry the weight of one car so that its contact with the socket is not so great as to exclude the ready entrance of a lubricant, whereas if the weight of both cars 35 were all placed upon a single pivot trunnion it would result in excluding the application of the lubricant due to the excessive weight, as I have found in practice.

It will now be seen that by reason of the 40 double or plurality of pivot trunnions, the two cars may freely articulate to accommodate their constantly changing relative position, for instance, when they reach the crest of the hill with one car on one slope on 45 one side of the crest and the other car on the other slope at the other side, at which time they will form an obtuse angle. Then again, when they reach the dip of a hill and come to the dip between two hills, they will 50 freely articulate so that one car will incline upward on one side of the dip and the other incline downward on the other side of the dip.

Then again, when the cars change their 55 lateral relative position as when going round a curve and at the same time have reached the crest of a hill, one car on one side and the other car on the other side of such crest or have reached the dip between two hills 60 with one car travelling downwardly on the hillside while the other car is travelling upwardly, they will be free to move and assume different relative positions laterally and also 65 assume an obtuse angle relatively to each other.

These are the several advantages that are derived from the use of the plurality of pivot trunnions or what I may term the double articulation of adjacent cars on the one bolster.

In so far as concerns the socket base plate and the two pivot trunnions, I call attention to the fact that these parts are shown and described, but unclaimed, in my application filed February 8, 1923, Serial No. 617662 for improvements in railway cars.

Having thus fully described my invention, what I claim as new and desire to secure by Letters Patent, is:

1. In a railway car, the combination with a truck bolster, and two adjacent cars, of a plurality of pivot trunnions and a corresponding plurality of sockets therefor, each car having one trunnion and one socket assigned to it.

2. In a railway car, the combination with a truck bolster, and two adjacent cars, of a plurality of pivot trunnions and a corresponding plurality of sockets therefor, each car having one trunnion and one socket assigned to it, and a locking device adapted to restrain either trunnion from displacement from its socket.

3. In a railway car, the combination with a truck bolster, and a base plate having sockets, of two adjacent cars, each having a pivot trunnion secured thereto and adapted each to occupy a socket.

4. In a railway car, the combination with a truck bolster and a base plate having sockets, of two adjacent cars, each having a pivot trunnion secured thereto and adapted each to occupy a socket, and a locking device comprising a removable member adapted to engage with the trunnions and prevent their withdrawal from the sockets.

5. In a railway car, the combination with a truck bolster and the platforms of two railway cars each projected over the bolster, of a socket base plate and a pivot trunnion for each platform, said trunnions being adapted each to enter one of the sockets.

6. In a railway car, the combination with a truck bolster and two car platforms each projected over the bolster, of a socket base plate secured to the bolster and two trunnion plates secured one to one platform and the other to the other platform and a pivot trunnion carried by each trunnion plate.

7. In a railway car, the combination with a socket base plate having sockets therein, of two pivot trunnion plates, each having a trunnion adapted to fit each in a socket, the trunnions having shoulders, and a locking bolt mounted in the socket plate and adapted to engage with said shoulders to prevent either trunnion from displacement.

In testimony whereof, I affix my signature.

THOMAS ELLIOTT,
